Patented Oct. 11, 1966

205,947

AMPLIFIER FOR ELECTRICAL MUSICAL INSTRUMENTS

Kenneth A. Hopkins, Farmington, and Stephen H. Kaminski, Warren, Mich., assignors to D. H. Baldwin Company, Cincinnati, Ohio, a corporation of Ohio

Filed Oct. 12, 1965, Ser. No. 87,440

Term of patent 14 years

(Cl. D26—14)

Fig. 1

Fig. 2

Fig.3

FIG. 1 is a plan view of an amplifier for electrical musical instruments embodying the new design.

FIG. 2 is a perspective view illustrating the front and one side thereof.

FIG. 3 is a perspective view illustrating the back and the other side thereof.

I claim:

The ornamental design for an amplifier for electrical musical instruments, substantially as shown.
